SHADOW SCOPE

James L. Cox, Ramsey, N. J., assignor to Duro-
Test Corporation, North Bergen, N. J., a corpo-
ration of New York

Application October 15, 1949, Serial No. 5,510

Term of patent 7 years

(Cl. D57—1)

To all whom it may concern:

Be it known that I, James L. Cox, a citizen of the United States, and a resident of Ramsey, in the county of Bergen, State of New Jersey, have invented a new, original, and ornamental Design for Shadow Scope, of which the following is a specification, reference being had to the accompanying drawing, forming part thereof.

In the drawing—

Figure 1 is a perspective view of the shadow scope showing my new design;

Figure 2 is a side elevational view thereof, the broken line being for illustrative purposes only.

Figure 3 is an end elevational view of the upper end; and

Figure 4 is an end elevational view of the lower end.

I claim:

The ornamental design for a shadow scope, as shown and described.

JAMES L. COX.
